STONE SETTING DEVICE FOR JEWELRY OR
OTHER APPLICATIONS

Victor Maynier, Paris, France, assignor to Société en nom Collectif V. Maynier & G. Pincon, Paris (Seine), France

Application January 5, 1937, Serial No. 119,115
In France June 24, 1936

4 Claims. (CL. 63—29)

This invention relates to a system of setting precious or imitation stones, applicable, in particular, to jewelry for securing these stones in their settings without having recourse to claws or to setting means. This system of setting is essentially characterized by the fact that the bottom portion of the stone is held stationary in a bezel, in the shape of a frustum-like cup, having a concave generatrix, by means of screws which are secured in the setting, parallel to the directing axis of the cup and the heads of which take a bearing on the bevel of the table of this stone. For thus securing the stone, use must be made of at least two screws symmetrically arranged about the stone and the cup receiving the latter.

In the accompanying drawings and by way of example:

Fig. 1 is a longitudinal section of a system of setting stones for jewelry, according to the present invention.

Fig. 2 is a plan view.

Fig. 3 is a cross section.

Fig. 4 is a partial elevation of another form of carrying out the subject-matter of the invention.

Fig. 5 is a plan view of a detail of Fig. 4.

As indicated above, the system of setting, forming the subject-matter of the invention, is characterized by the fact that the stones are secured in bezels, in the shape of frustum-like cups, by the action of screws, which are engaged in lugs of these bezels and take a bearing on the bevelled portion of the table of these stones. These bezels 1 are made in one piece and are obtained, for instance, by pressing; their inner conical surface 2 is generated by a concave generatrix 3, so that the bottom portion 4 of the stone 5 bears according to two circular lines 6, on the said surface.

In the embodiment of Figs. 1 to 3, the bezels 1 are provided with at least two lugs 7 in which are formed inner screw threads 8, the axes of the latter being parallel to the directing axis of the frustum-like or tapered surface internally bounding each cup.

In the example shown in Figs. 1 to 3, the lugs 45 7 are three in number and are diametrically arranged, and each lug is, moreover, common to two contiguous bezels. The screws 9 have a rounded head 10, a button-head for instance, and the lower face 11 of which is tapered, this allowing them to take a bearing, according to one generatrix only, on the bevel 12 of the table 13 of the corresponding stone 5. The latter cannot thus be scratched by the contact of a claw or of a beaded ledge and no metal part practically conceals the stone thus set.

In the case of a jewel constituted by a plurality of contiguous stones (bar-brooch for instance), any bending of the setting will be avoided by securing, between the lugs 7 of the bezels 1, metal rings 14 (made of wire of suitable cross section). Welded cross members 15 connect, moreover, these rings to the lower edge of the frustum-like cups constituting the bezels. 5

Figs. 4 and 5 illustrate a second embodiment according to which the stones 5 are hingedly connected to each other. For each stone is provided an individual bezel 1 which, with the ring 14 secured to its lower part by means of the welded cross members 15, is so shaped as to externally present a downwardly tapered surface. On the sides of each of these bezels are welded, at diametrically opposed points, small tubes 16 internally screw threaded for receiving the screws 9. 15

A horizontal slot 17 is formed in the tubes 16 below the bezel. Before screwing the screws 9 in the tubes 16, the eyelets 19 of a small bar or link 18 are inserted in the slots 17, so that the screws 9 pass through the eyelets 19 and that the two adjacent bezels 1 are hingedly connected together. The stones 5 are secured in the bezels 1, in a manner similar to that shown in Figs. 1 to 3, by the heads 10 of the screws 9 taking a bearing on the bevel 12 of the table 13 of the stones. Any number of stones can be connected as a single chain by the joint system which has just been described. 25

Constructional modifications can be made in the means above set forth without departing thereby 30 from the scope of the present invention. 35

What I claim is:

1. System of setting stones for jewelry or other applications, comprising bezels each having internally a surface in the shape of a tapered cup with concave generatrix, a stone inserted in each bezel, screws secured on the sides of each bezel and bearing through their heads on the edge of the stone inserted in the bezel, and a connecting member arranged between each pair of adjacent bezels and having its ends pivoted on the screws secured on the sides of these bezels. 40

2. A means of setting stones for jewelry or other applications comprising at least two ring-shaped bezels forming a range, each bezel underlying the edge of a stone and having internally a surface in the shape of a tapered cup, a stone inserted in each bezel and screws secured in the bezels, substantially in the middle plane of the range of the bezels, and bearing through their 50 55

heads on diametrically opposed points of the edge of each stone.

3. A means of setting stones for jewelry or other applications comprising at least two ring-shaped bezels forming a range, each bezel underlying the edge of a stone and having internally a surface in the shape of a tapered cup with concave generatrix, a stone inserted in each bezel and screws secured in the bezels, substantially in the middle plane of the range of the bezels, and bearing through their heads on diametrically opposed points of the edge of each stone.

4. A means of setting stones for jewelry or other applications, comprising bezels each having internally a surface in the shape of a tapered cup, a stone inserted in each bezel, screws secured on the sides of each bezel and bearing through their heads on the edge of the stone inserted in the bezel, and a connecting member arranged between each pair of adjacent bezels and having its ends pivoted on the screws secured on the sides of these bezels.

VICTOR MAYNIER.
